UNITED STATES PATENT OFFICE.

WILLIAM H. MYERS, OF NEW YORK, N. Y., ASSIGNOR TO UNION STOVE WORKS, OF NEW YORK, N. Y., A CORPORATION OF NEW YORK.

COMPOSITE STOVE.

1,383,965.

Specification of Letters Patent.

Patented July 5, 1921.

Application filed September 11, 1917. Serial No. 190,826.

To all whom it may concern:

Be it known that I, WILLIAM H. MYERS, citizen of the United States, residing at New York, in the county of New York and State 5 of New York, have invented certain new and useful Improvements in Composite Stoves; and I do hereby declare the following to be a full, clear, and exact description of the invention, such as will enable others skilled in 10 the art to which it appertains to make and use the same.

This invention relates to cooking stoves, and the novel features thereof are herein-after described, illustrated in the accompanying drawings, wherein a single embodiment is shown, and embraced within the scope of the appended claims.

In said drawings,—

Figure 1 is a perspective view of the monolithic body portion,

Fig. 2 is a longitudinal vertical sectional view through the complete stove,

Fig. 3 is a horizontal sectional view as on the line 3—3 of Fig. 2,

Fig. 4 is a vertical cross-sectional view as on the line 4—4 of Fig. 2,

Fig. 5 is a detailed perspective view showing small sections of the door frame and their mounting, and

Fig. 6 is a plan view of the portion of the body of the stove showing the fire-box.

In the construction of the stove as herein described raw products easily obtained in the territory in which the stove is to be used 35 will be converted into a plastic composition, and by the use of templets, a body portion for the stove, including all of the required features of construction for subsequent addition of necessary fittings, may be easily 40 formed.

When the body portion has been completed, a fire-box, oven, cover and door-frames may be quickly attached thereto to form a complete stove. When considered in 45 the light of an article used mostly in export trade, it is easily understood how this reduction of the major portion of the breakable parts produces a great saving in crating, and expense in shipment, and elimination 50 of breakage in transportation. Other advantages will be presently explained.

Referring more specifically to the drawings, there is shown a body portion comprising a back wall 10, end walls 11 and 12, 55 front wall 13 and bottom 14. These parts

will preferably be made of plastic material, as cement, placed in templets or forms to produce the construction which provides for the proper assembly of the fittings furnished for the stove. The end wall 11 has the lower 60 portion increased in thickness to provide a shoulder 15. A parting wall or web 16 extends across the upper face of the bottom 14 and this web has its upper edge terminating in a plane on a level with the shoulder 15. 65 This web forms a compartment 17 for the ash pit, and a compartment 18 for the oven.

The front wall has openings formed therein by having extensions 19 and 20 from the forward ends of the end walls 11 and 12, 70 and by the column 21 rising in front of the forward end of the web 16.

The fire-box including a metallic container 22, grate 23 pivotally mounted therein, and fire brick 24, is placed in the body portion 75 of the stove so that the lower edges of the side wall of the box 22 rest upon the shoulder 15 and the upper edge of the web 16. When the fire-box is placed within the body portion, a space 22' is formed between the 80 adjacent walls of the fire-box and body. This space provides for insulation in the form of a dead air space. Asbestos or other insulating material may be placed between the metallic wall 22 and the walls of the 85 body, if desired.

An oven 25 is placed in the chamber 18 and is provided with a flange 26 formed about the open end thereof to receive fastening means. Another flange 27 rises from the 90 rear upper edge of the oven and a similar flange 28 extends along its rear side, these flanges constituting flue guides which direct the course of the heated air currents across the top of the oven and through the flue 95 formed by the side wall of the oven and the end wall 12. The flue then extends between the bottom of the oven and the top wall of the bottom 14 of the body where a diagonally disposed guide 29 is arranged for 100 the purpose of uniformly deflecting the travel of the heated air. After passing about the flue guide 29, the air currents are directed rearwardly under the oven and upwardly through the flue 30 formed be- 105 tween the rear wall of the oven and the rear wall of the body. In this manner, it will readily be seen that the force of the draft and the fire travel will confine the heat around and against the metallic parts, 110

and in fact, away from the cement body or shell. The parts of the stove which receive the direct heat are formed of metal, while the parts which receive indirect heat are 5. constructed of plastic material, as cement. This combination would result in an economy of heat, the cement body, being refractory to heat as compared to metal, would prevent its escape. As a corollary 10 of this point, there would be the advantage of persons in tropical countries who desire stoves that do not radiate heat in the kitchen.

The openings in the front wall are provided with closures supported by frames 15 which are detachably carried by the front wall of the body. The frames of the fire-box compartment are denoted by 31 and 33, the same being clamped about the extensions 19 and 21 by bolts 32. Another frame 34 is 20 clamped to the flanges 26 of the oven by bolts 32. Frames 33 and 34, respectively, support closures 35 and 36.

The side walls 10, 11 and 12, the extensions 19 and 20, and the column 21 support 25 a cover 37 having a depending flange 38 lying contiguous the inner edges of the walls, extensions and column. This flange is so positioned on the under face of the cover with respect to the top as to allow for liberal 30 expansion of the metallic top without damaging the side walls, while at the same time, it forms an effective seal against the escape of smoke or gases through the joint 45 formed by the cover and the side walls. 35 The cover is also provided with depending flange 39 which extends across the front of the body, with portions thereof partially projected along the upper edges of the end walls 11 and 12. The flanges 38 and 39 40 across the front wall reinforce the cover, and afford support for the upper edges of the frames 33 and 34, and the upper flange of the oven as shown at 26. The cover will be provided with the usual detachable lids 45 and lid-supporting section, and it will also have the usual flange 40 to receive the smoke pipe.

The fire-brick 24 along the side next to the oven will rise to a plane equal with the 50 top of the oven to afford ample flue space from the fire-box, and the flange 27 may be provided with the usual damper to by pass the smoke and air current when the fire has just been started, or when it is desired to cool 55 the oven 25 to a slight degree. The flange 38 lying directly behind the opening formed by the damper, will preferably be of slightly greater depth to form a shield to protect the portion of the rear wall lying behind this 60 damper.

As explained at the outset, it is contemplated in the selling of these stoves to ship

to customers metallic parts together with templets and specifications for constructing at destination the cement or plastic body. 65 There results a saving of more than fifty per cent. in metal alone. This constitutes an extremely important factor. Damage to the stoves in shipment is reduced to a minimum, in fact, the lessening of damage to the goods 70 in transit would be proportionate to the reduction of the use of metal in the stove construction, that is to say, more than fifty per cent.

With the ordinary range made of cast 75 iron or other metal, replacement of repair parts are frequently made, such as grates, tops, oven plates, etc. There comes a time, however, after a few years' use of the stove or range, when it becomes impracticable to 80 introduce new parts therein for the reason that the other parts become gradually warped through the heat and atmospheric conditions, and also deteriorate through oxidation, so that new parts will not properly 85 adjust to the old, rendering the stove useless. With the cement range, the facility by which the parts may be replaced, renders the stove very much more durable than other stoves, the cement body not being subject to the drawbacks mentioned. 90

Having thus described this invention I claim:

1. A stove comprising a plastic monolithic body having back and end walls, and an elevated bottom, a web extending across said body portion in spaced relation so as to form compartments in said body, a column rising from the forward end of said web, one end wall having a shoulder formed thereon level 95 with the top of the web, a fire-box supported by said web and shoulder, a front wall formed by inwardly projecting portions of the forward extremities of the end walls, an extension rising from the forward end 100 of the elevated bottom in front of one of the compartments, and an oven sustained above the bottom at a height substantially equal to the height of the extension. 105

2. A stove including bottom, end, back 110 and front walls integrally formed from a plastic composition suitably molded, said front wall being formed by inwardly projecting portions of the forward extremities 115 of the end walls, and by an extension rising from the forward edge of the bottom wall, thereby providing an opening, and a top for the stove.

In testimony whereof I affix my signature in presence of two witnesses:

WILLIAM H. MYERS.
